UNITED STATES PATENT OFFICE

124,430

DESIGN FOR A COMBINED BOTTLE BREAKER AND CAP REMOVER

Frank J. Vesce, Revere, Mass.

Application March 26, 1940, Serial No. 91,247

Term of patent 7 years

To all whom it may concern:

Be it known that I, Frank J. Vesce, a citizen of the United States and a resident of Revere, county of Suffolk and State of Massachusetts, have invented a new, original, and ornamental Design for a Combined Bottle Breaker and Cap Remover, of which the following is a specification, reference being made to the accompany drawing, forming part thereof.

In the drawing:

Fig. 1 is a front elevational view of a combined bottle breaker and cap remover, showing my new design; and

Fig. 2 is a side elevational view thereof, a portion of the guard for bottle breaker being shown broken away; and

Fig. 3 is a sectional view, taken along line 3—3 of Fig. 2.

I claim:

The ornamental design for a combined bottle breaker and cap remover, as shown and described.

FRANK J. VESCE.
